UNITED STATES PATENT OFFICE

151,854

DESIGN FOR A CHICKEN FRYER

Emil O. Mehline, Seattle, Wash.

Application March 7, 1947, Serial No. 137,428

Term of patent 7 years

(Cl. D44—1)

To all whom it may concern:

Be it known that I, Emil O. Mehline, a citizen of the United States, residing at Seattle, King County, Washington, have invented a new, original, and ornamental Design for a Chicken Fryer, of which the following is a specification, reference being had to the accompanying drawing, forming a part thereof, in which

Fig. 1 is a perspective view of a chicken fryer, showing my new design;

Fig. 2 is a perspective view with the cover raised.

Fig. 3 is a cross-sectional view taken through plane 3—3 of Fig. 1;

Fig. 4 is a top plan view;

Fig. 5 is a side elevational view;

Fig. 6 is an end view of the same.

I claim:

The ornamental design for a chicken fryer, as shown.

EMIL O. MEHLINE.
